UNITED STATES PATENT OFFICE.

JOHN J. DENNIS, OF CHICAGO, ILLINOIS, ASSIGNOR OF ONE-HALF TO F. W. FULLMER AND F. E. BALL, OF CHICAGO, ILLINOIS.

ADJUSTABLE SCAFFOLD-BRACKET.

No. 853,344.

Specification of Letters Patent.

Patented May 14, 1907.

Application filed October 26, 1905. Serial No. 284,432.

To all whom it may concern:

Be it known that I, JOHN J. DENNIS, a citizen of the United States, and a resident of the city of Chicago, in the county of Cook and State of Illinois, have invented certain new and useful Improvements in Adjustable Scaffold-Brackets; and I do hereby declare that the following is a full, clear, and exact description of the same, reference being had 5 to the accompanying drawings, and to the letters of reference marked thereon, which form a part of this specification.

This invention relates to improvements in adjustable scaffold brackets of that class 15 adapted to be adjustably secured upon a suitable support therefor.

Scaffold brackets heretofore constructed have not usually been capable of ready adjustment to different sizes of upright or variously inclined supports and this has frequently occasioned inconvenience. Furthermore the brackets heretofore devised for this purpose have not been extensible to increase the length of the bracket or afford a 25 wider scaffold.

The object of this invention is to afford a scaffold or other bracket either for inside or outside use capable of adjustment instantaneously to its support to enable a horizontal scaffold to be built thereon independent 30 of the inclination of the support from a perpendicular.

It is a further object of the invention to so construct a bracket as to enable it to be 35 quickly adjusted to different thicknesses of the supports and also to so construct it that should the plank or other support be warped or sprung transversely the same will nevertheless be firmly engaged by the bracket.

Furthermore, inasmuch as in building 40 scaffolds it frequently is very desirable to afford a guard or lateral support to prevent tools or materials used by the workmen from falling from the scaffold it is an object 45 of the invention to provide means for accomplishing this and also to enable the width of the scaffold to be increased should it be desired.

It is a further object of the invention to 50 afford a support capable of being knocked down into very small compass and affording a very strong, simple and durable construction affording maximum safety to the user and at all times affording binding engage-

ment upon its support and incapable of slipping.

The invention consists in the matters hereinafter described and more fully pointed out and defined in the appended claims.

In the drawings: Figure 1 is a side elevation of a device embodying my invention in use showing the extension arm retracted. Fig. 2 is a top plan view of the same with the support and staging plank removed. Fig. 3 is a section taken on line 3—3 of Fig. 2 with the extension arm turned outwardly and its adjustment indicated in dotted lines. Fig. 4 is a section taken on line 4—4 of Fig. 2. Fig. 5 is a side elevation of brackets embodying my invention showing the same employed to afford a temporary stairway. Fig. 6 is a side elevation showing the brackets employed to afford a scaffold both on the inner and outer side of the support.

As shown in said drawings: A, A' and A² indicate inclined supports which may be plank or other dimension stuff or any suitable support, arranged to incline or perpendicularly as preferred. Secured on said supports are the brackets which comprise two relatively adjustable jaws B—C. The outer jaw B is provided with integral arms b which extend downwardly, then horizontally and rearwardly from the jaw and as shown are provided on the under side thereof from a point below the gripping edge of the jaw with forwardly and downwardly inclined notches b'. The jaw B is provided on its inner edge and near its ends with a plurality of sharp teeth b², and as shown nearer the middle of the head with longer teeth b³ between which at the middle of the jaw the edge curves slightly inward and is provided with finer teeth b⁴ adapted to engage the plank or other support should the same be slightly warped. At the extremity of each arm b and on the inner side of the same is an integral or other suitable stud b⁵ to afford means for slidably engaging the complementary jaw C therewith. The inner jaw C as shown, is curved oppositely at its middle from the jaw B and is provided with teeth c², c³ and c⁴ corresponding with the teeth b², b³ and b⁴ on the outer jaw B and said jaw C inclines obliquely downward and forwardly to engage the support at an angle with the plane of the jaw B thus engaging the support at an effective angle, and when

weight is applied to the bracket forcing the teeth on each jaw into the support. Said jaw C is provided at its ends with integral extensions c^5 adapted to engage in the slots 5 or notches b' in the arms b and an integral plate c^6 is provided thereon which extends upwardly on the outer side of the arm and acts to hold the arms from any tendency to spread. Integrally connected with the jaw C are rearwardly directed longitudinally slotted arms c through which extend said studs b^6 which are permanently secured in engagement therewith by means of a washer c^7 . Said washers are permanently engaged 15 on the studs b^6 by riveting the ends of the studs down thereon. The rear ends of the arms c are each integrally connected with a rear bar or rail c^8 the inner or adjacent ends of which are connected by means of a pivot 20 or bolt d on which is pivoted an extension arm D. Said extension arm is provided with segmentally arranged apertures concentric with the pivot bolt d and adapted to receive a suitable pin therein which by engagement 25 on a downwardly directed rib d^3 on the rails c^8 acts to support the arm in adjusted position either horizontally or at a desired inclination as shown in dotted lines in Fig. 3.

30 The operation is as follows: The plank or support A, A' or A² is passed between the jaws of the bracket or brackets and secured in an upright position or at a desired inclination dependent upon the use to which the 35 brackets are to be applied. If the brackets are used to afford a temporary stair, as shown in Fig. 5, the angle may be such as will be suitable for such a purpose. The jaws are arranged by adjusting the outer 40 jaw as desired and then sliding the inner jaw into position to positively engage the opposite sides of the plank to support the brackets in a horizontal position. The extended projections c^5 on the jaw C in any case engage 45 in the notches below the arms b as shown in Fig. 1 and firmly hold said jaws in adjusted position. Two such supports and sets of brackets having been placed in proper relation, planks E—E' may be laid across 50 the same to afford steps as shown.

Ordinarily, of course, the brackets are used in building either inside or outside scaffolds or stagings and when so used may be used with a single plank for a staging or the width 55 may be increased either by turning the extension arm D downwardly into alignment with the top of the bracket arms $b-c$ as shown in Fig. 6 and a scaffold of double width provided by placing an additional 60 plank E' thereon, or an additional bracket may be engaged on the inner face of the support A² adjacent the wall, as shown in Fig. 6, and a plank E² supported thereon thus providing 65 a staging on both sides of the support and the staging may be made still wider by

the use of the extension arm on the last named bracket.

Obviously the brackets or jaws may be arranged for adjustment toward or from each other in any suitable manner and any suitable means may be employed to positively engage the same together in adjusted position.

I claim as my invention:

1. A bracket of the class described comprising relatively adjustable jaws having inwardly facing engaging edges thereon and integral slidably engaged arms on said jaws extending in the same direction and adapted to afford a support. 75

2. A device of the class described comprising relatively adjustable jaws having inwardly directed sharp edges adapted to engage a suitable support, a horizontal arm engaged on each end of one of said jaws and provided with a plurality of notches in the under side thereof, means for slidably engaging the other jaws longitudinally of said horizontal arms and laterally directed projections thereon adapted to engage in said notches and hold said jaw in adjusted position. 80 85

3. A device of the class described comprising mutually adjustable jaws, similarly directed arms on each jaw, those on one jaw being slidably engaged with those on the other and means on the last named jaw 95 adapted to interlock with the arm of the other jaw.

4. A scaffold bracket of the class described comprising relatively adjustable jaws having inwardly directed toothed edges adapted to engage a supporting member therebetween, arms on the ends of said jaws extending in the same direction, the ends of those of one jaw engaging in slots in the others, said arms 100 105 affording a support for a staging.

5. A bracket comprising adjustable jaws adapted to grip an inclined support therebetween, means rigidly engaging the jaws in adjusted relation and a rigid arm on each end 110 of each jaw together affording a substantially horizontal staging support those on one jaw being slidably and pivotally engaged with those on the other.

6. The combination with an outer jaw having inwardly directed notched arms, of an inner jaw adjustable relatively to the outer jaw, slotted arms thereon slidably engaged on those of the outer jaw, lugs integrally connected therewith and engaging in the notches 120 of the outer arm and means on the inner arms adapted to prevent the outer arms from spreading, the arms of one or both of said jaws being rigidly connected at the rear end. 115

7. In a device of the class described the combination with a jaw of parallel arms thereon provided with notches in their under sides, a coacting jaw, arms thereon extending in the same direction as the aforesaid arms and lying within the same, laterally directed 125 130

extensions on the ends of said last named jaw adapted to engage in said notches and devices on the first named arms slidably connected in the last named arms.

8. In a device of the class described the combination with a jaw having inward directed teeth for the entire length thereof, rearwardly extending arms engaged thereto and extending in a different plane from the plane of said jaw, a jaw having inward directed teeth corresponding with the teeth on the aforesaid jaw, rearward extending, slotted arms connected with the last named jaw, an extension on one end of each of said arms and a plate on each extension adapted to prevent the first named arms from spreading laterally.

9. In a device of the class described the combination with a jaw having inward directed teeth of different sizes, an arm on each end of said jaw, a lug on each end of said jaw a jaw having inward directed teeth, arms rigidly engaged to said last named jaw and notched to engage said lugs and means on said last named arms adapted to engage in the slots of the first named arms thereby permitting different adjustments.

10. As an article of manufacture an extensible bracket of the class described having relatively adjustable gripping jaws adapted clampingly to engage a support, one of said jaws being arranged at an angle with the plane of the other and pivotally and slidably connected therewith.

11. As an article of manufacture a bracket of the class described embracing relatively adjustable gripping jaws having toothed edges and adapted to clampingly engage a supporting element, one of said jaws being arranged obliquely with the plane of the other, slotted arms on one jaw provided with a lateral projection on the inner end of each arm, a plate rigidly engaged to said projection, notched arms on the other jaw adapted to engage on said projections for rigidly holding said jaws in adjusted position and provided with pins at their outer ends slidably and pivotally connected in said slots.

12. The combination with an outer jaw having the engaging edge horizontally di-

rected, of an inner jaw having an obliquely and outwardly directed engaging edge, slotted and notched arms on said jaws slidably engaged together and affording a scaffold support and laterally directed projections on said arms adapted to engage in said slots and notches.

13. In a device of the class described a scaffold bracket or clamp having complementary engaging jaws arranged at an angle with each other, integral arms engaged to the ends of said jaws affording a scaffold support and the arms of one jaw slidably longitudinally of the other, the arms on one jaw being notched and those on the other slotted, means on said arms adapted to engage in said slots and notches and hold the jaws in adjusted position, an extensible arm pivoted on the rear end of said arms on one jaw and a segment thereon affording adjustment of the same relatively of said arm.

14. In a device of the class described the combination with a plurality of jaws, slotted arms rigidly engaged on the ends of one jaw, notched arms integral with the ends of the other jaw, a rod connecting the extremities of said slotted arms, an extension arm pivoted centrally on said rod and having a plurality of apertures arranged on the pivoted end and means for engaging any one of said apertures and adapting said arm to be adjusted at any angle.

15. In a device of the class described the combination with a jaw having parallel, slotted arms thereon integrally connected at their outer ends, a coacting jaw having parallel, notched arms thereon slidably engaged on the outer side of the aforesaid arms, studs on said notched arms slidably engaged in the slots of the first named arms and means on the first named jaw adapted to engage in the notches of the last named arms.

In testimony whereof I have hereunto subscribed my name in the presence of two subscribing witnesses.

JOHN J. DENNIS.
